[57] CLAIM

The ornamental design for a handbag, as shown and described.

DESCRIPTION

FIG. 1 is a perspective view of a handbag showing my new design;

FIG. 2 is a reduced scale perspective view thereof showing the side panels in a horizontal position;

FIG. 3 is a rear elevational view of FIG. 1;

FIG. 4 is a right and elevational view;

FIG. 5 is a top plan view; and

FIG. 6 is a bottom plan view.

The characteristic feature of the design resides in the fold-out side panels.
